UNITED STATES PATENT OFFICE

126,559

DESIGN FOR A CABINET FOR A VENDING MACHINE

John F. Meyer, Chicago, Ill., assignor to Exhibit Supply Company, Chicago, Ill., a corporation of Illinois

Application December 21, 1940, Serial No. 97,509

Term of patent 7 years

To all whom it may concern:

Be it known that I, John F. Meyer, a citizen of the United States and a resident of Chicago, in the county of Cook and State of Illinois, have invented a new, original, and ornamental Design for a Cabinet for a Vending Machine, of which the following is a specification, reference being had to the accompanying drawing, forming a part thereof, and in which the single figure is a perspective view of a cabinet for a vending machine, showing my new design.

I claim:

The ornamental design for a cabinet for a vending machine, as shown.

JOHN F. MEYER,
